UNITED STATES PATENT OFFICE.

HENRY GOLDBLATT, OF KANSAS CITY, MISSOURI.

PLASTERER'S FLOAT.

Application filed November 25, 1927. Serial No. 235,540.

My invention relates to improvements in plasterer's floats.

One of the objects of my invention is to provide a novel plasterer's float, of the type 5 provided with a flexible pad, with novel means by which a worn pad may be quickly removed and replaced by a new one.

A further object of my invention is the provision of novel means by which the pad 10 is stretched and held tightly clamped along its edge portions.

A further object of my invention is the provision of novel means for properly registering the pad upon its being mounted on 15 the float.

Still another object of my invention is to provide a device of the kind described, which is simple, cheap, durable, not liable to get out of order, which is efficient in operation 20 and which permits of the quick and easy insertion into or removal from of the pad with respect to the pad holding members.

A further object of my invention is the provision of two clamping members so arranged with respect to each other that a pad 25 clamped therebetween will extend across the inner member and below the lower edges of of the outer member.

The novel features of my invention are 30 hereinafter fully described and claimed.

In the accompanying drawing, which illustrates the preferred embodiment of my invention,

Fig. 1 is a top view of my improved float, 35 with the parts shown in the operative position.

Fig. 2 is a cross section on the line 2—2 of Fig. 1.

Fig. 3 is a stretchout view of the pad.

Fig. 4 is a plan view of the frame and 40 clamping member hinged thereto, the latter being shown in the open position.

Fig. 5 is a reduced side elevation of my improved float.

Similar reference characters designate similar parts in the different views.

My improved float comprises two clamping members 1 and 2, the latter being movable to and from a clamping position in the member 1, and in the latter position being adapted to clamp the edge portions of a flexible pad 3 against the inner walls of the outer member.

In the preferred embodiment of my invention 45 the outer clamping member 1 comprises

a rectangular frame open at the top and bottom and the member 2 comprises a flat plate 2 having upwardly extending side flanges 4 and end flanges 5, Figs. 1 and 2.

One of the flanges 4 has attached to it two 60 hinges 6 which are also attached to one side of the frame 1, in a manner such that the clamping member 2 may be swung from the open position, shown in Fig. 4, to the closed clamping position, within the frame 1, as 65 shown in Figs. 1, 2 and 5. In such clamping position the bottom of the plate 2 projects, preferably, below the bottom edges of the frame 1, as shown in Fig. 2.

To the upper side of the plate 2 is fastened 70 a handle 7, with which the float may be held during its operation, and also for forcing the pad within the frame 1.

The pad 3 is of greater area than the frame 1, the inner walls of which are spaced 75 from the adjacent edges of the clamping member 2, when the latter is in the clamping position.

Each end of the frame 1 is provided with 80 an inwardly extending projection 8 which is adapted to engage the pad 3 to hold the latter from slipping after its insertion in the frame 1.

One edge of the pad 3 is provided with 85 two notches 9 which are adapted to receive the hinges 6, and which are so disposed so as to properly register the pad with the frame 1.

In mounting the pad on the float clamping members 1 and 2, the pad is laid over the top 90 of the frame 1 with the hinges 6 in the recesses or notches 9. The member 2 is then swung by means of the handle 7 into the frame 1, thus forcing the pad 3 into said frame with the edge portions of the pad extending upwardly and held tightly clamped between the clamping member 2 and the inner walls 95 of the frame 1. This operation stretches the pad 3 lengthwise and crosswise across and bearing against the bottom of the plate 2, with the bottom of the pad projecting below the bottom edges of the frame 1, which enables the float to be tipped, in its use, without the frame 1 contacting with the material operated upon by the pad 3.

To releasably hold the clamping member 2 in the clamping position, any suitable means may be employed, such as a screw 10, which is removably extended through a transverse hole 11, Fig. 2, in the adjacent 105

110

side of the frame 1, and through a transverse hole 12 in the adjacent upturned portion of the pad 3, said screw being removably fitted in a threaded hole extending 5 transversely through the adjacent flange 4.

When it is desired to replace a worn pad with a fresh one, the screw 10 is removed, and the clamping member 2 then swung, by means of the handle 7, to the open position shown 10 in Fig. 4, thereby releasing the pad 3, upon which it may be replaced, in the manner already described, by another pad, after which the screw 10 is reinserted through the holes 11 and 12 and in the threaded hole in 15 the adjacent flange 4.

By having the pad 3 bearing directly against the bottom of the clamping plate 2, the frame 1 may comprise simply a metal strip formed into a rectangle and having its 20 end portions united, as shown.

By hinging the members 1 and 2 to each other, said members are always retained in their proper cooperative relationship to each other and to the pad 3, when the latter is 25 being inserted, they are not liable to individual loss one from the other, and it enables the locking device 10 to be easily and quickly operated to connect the members.

I do not limit my invention to the structure shown and described, as many modifications, within the scope of the appended 30 claims may be made without departing from the spirit of my invention.

What I claim is:—

1. A plasterer's float comprising a holding frame open at the top and bottom, a clamping member hinged thereto so as to be swung to and from a clamping position within said frame, and a flexible pad of greater area than the area enclosed by said frame and adapted 40 to be extended across said frame and to be forced thereinto by and to bear against the bottom of said clamping member and to have its edge portions extended upwardly through the bottom of said frame and tightly clamped by and between the edges of said clamping member and the inner walls of said frame.

2. A plasterer's float comprising a holding frame open at the top and bottom, a clamping member hinged thereto so as to be swung to and from a clamping position within said frame, a flexible pad of greater area than the area enclosed by said frame and adapted to be extended across said frame and to be forced thereinto by and to bear against the bottom of said clamping member and to have its edge portions extended upwardly through the bottom of said frame and tightly clamped by and 55 between the edges of said clamping member and the inner walls of said frame, and means releasably connecting the frame and clamping member for holding the latter in the clamping position.

3. A plasterer's float comprising a holding

frame open at the top and bottom, a clamping member movable to and from a clamping position within said frame, and a flexible pad of greater area than the area enclosed by said frame adapted to be forced by said clamping member into said frame so as to be stretched tightly across and to bear against the bottom of said clamping member and to be extended upwardly through the bottom of said frame and held tightly clamped between the edges of the clamping member and the inner walls of said frame.

4. A plasterer's float comprising a rectangular holding frame, a clamping member having a hinge connecting it with one side of said frame so that it may be swung to and from a clamping position within said frame, and a flexible pad of greater area than the area enclosed by said frame and having an edge registering notch adapted to receive said hinge, said pad being adapted to be forced by said clamping member into said frame so as to be stretched tightly across said clamping member and to be held clamped between the edges of the latter and the inner walls of said frame.

5. A plasterer's float comprising two members hinged to each other, one of which is insertible to and from a clamping position within the other, the outer member being open at the top and bottom, and a flexible pad of greater area than the area of the outer member and adapted to be forced into and to bear against the bottom of the outer member by the inner member and to have its edge portions extended upwardly through the bottom of said outer member and clamped between said members.

6. A plasterer's float comprising a rectangular frame each end of which has an inwardly extending projection, a clamping member hinged to one side of said frame and movable to and from a clamping position within said frame, and a flexible pad of greater area than the area enclosed by said frame and adapted to be forced by said clamping member into said frame and into engagement with said projections and to have its edge portions extended upwardly through the bottom of said frame and clamped between said frame and said clamping member.

7. A plasterer's float comprising a rectangular frame each end of which has an inwardly extending projection, a clamping member having a hinge connecting it with one side of said frame and movable to and from a clamping position within said frame, and a flexible pad of greater area than the area enclosed by said frame and having an edge notch adapted to receive said hinge and adapted to be forced into said frame and to be held clamped by said clamping member against the frame and said projections.

8. A plasterer's float comprising two clamping members, one of which is movable

to and from a position within the other, the outer member being open at the top and bottom, and a flexible pad of greater area than the area enclosed by the outer member and which is adapted to be stretched across and to bear against the bottom of the inner member and to have its edge portions extended up-

wardly through the bottom of said outer member and clamped between said members, and when so clamped extending below the bottom edges of the outer member. 10

In testimony whereof I have signed my name to this specification.

HENRY GOLDBLATT.
